UNITED STATES PATENT OFFICE.

JAMES M. HORNADAY, OF DURHAM, NORTH CAROLINA, ASSIGNOR TO LIGGETT & MYERS TOBACCO COMPANY, OF ST. LOUIS, MISSOURI, A CORPORATION OF NEW JERSEY.

CUTTING MECHANISM FOR CIGARETTE-MACHINES.

1,143,628.

Specification of Letters Patent. Patented June 22, 1915.

Application filed March 3, 1914. Serial No. 822,143.

To all whom it may concern:

Be it known that I, JAMES M. HORNADAY, a citizen of the United States, residing at Durham, in the county of Durham and State 5 of North Carolina, have invented new and useful Improvements in Cutting Mechanism for Cigarette-Machines, of which the following is a specification.

This invention relates to improvements in 10 cigarette making machines of the continuous rod type, and particularly to the cut-off mechanism for severing the rod into cigarette lengths, and has as its primary object to provide a light simple direct acting mechanism, free of all lateral or torsional strains 15 whereby greater speed may be attained with better results than heretofore.

By means of the novel construction and arrangement herein shown and described, 20 the longitudinal and angular movements of the several parts are imparted by power applied respectively in the longitudinal axial line of the reciprocating supporting member, and around said axis as a center. The 25 power thus applied being direct, friction is lessened, strains eliminated, the parts made lighter, the power required to run the mechanism decreased, and the possible speed of the machine materially increased.

30 In the drawings, Figure 1 is a top plan view of the cut-off mechanism. Fig. 2 is a side elevation of the same. Fig. 3 is a cross sectional view on the line 3—3 of Fig. 2. Fig. 4 is a similar section on the line 4—4. 35 Fig. 5 is a perspective view of a clamp block forming a part of the invention.

In the drawings, 10 indicates a portion of the stationary main frame of a continuous rod cigarette machine upon which frame two 40 bearings 11 are rigidly mounted in spaced relation lengthwise of the machine to sustain opposite ends of a longitudinally reciprocating bar or slide 12 which carries the entire rod cutting mechanism. The central 45 portion of the bar 12 is preferably circular in cross section, as shown, with ends 13, 14 of a shape other than circular. In the present embodiment these ends are square and slide in similarly shaped bearings or guides 50 11; they may however be oval, hexagonal or of other form to prevent rotation of the bar in its bearings. These guides 11 preferably have a geometrical axis coinciding with the longitudinal axis of the bar or slide. A lug

15 projects from one end 13 of the bar 12 to 55 which is pivoted a connecting rod 16 operated by an eccentric 17 on a continuously revolving shaft 18. A crank or other equivalent means may be substituted for the eccentric if found more suitable. The pivot 19 60 of the connecting rod 16 passes through the lug 15 in the longitudinal center of the bar 12, its axis and the axis of shaft 18 intersecting the axis of said bar at right angles, thus enabling the bar to be moved in its 65 bearings by a direct pull and thrust, free from side or torsional strains. Mounted to swing angularly about the axis of the bar on the round portion thereof is a frame or arm 20 carrying a circular, disk-like knife 70 21. The frame 20, in the form shown, consists of two tubular parts 22 that surround the central portion of the bar 12 and are retained in position thereon against end-wise movement by two fixed collars 23, 24. 75 From each tubular part a leg 25 extends upward and these legs are connected at their upper ends by a flat circular plate 26 upon which a like plate 27 rests and is clamped thereto by a through bolt 28. From the 80 plate 27 a bracket 29 extends that supports a long two-part tubular bearing 30, 31, integral with the bracket 29, in which revolves a shaft 32 with a belt pulley 33 at one end and the circular knife 21 on the other 85 end. As thus supported, the frame 20 with the circular knife 21 can rock freely in an angular direction on the bar 12 around its longitudinal axis.

Mounted rigidly but adjustably upon the 90 bar 12 and movable longitudinally therewith is a tubular guide 34 for sustaining the cigarette rod while being cut into cigarette lengths. The guide, in this form of the invention, comprises a body 35 through 95 which is made a horizontal perforation running parallel with the axis of bar 12 and intersected by a slot 36 at right angles to the perforation into and out of which the cutting edge of the circular knife is adapted 100 to swing. The body 35 is firmly connected to the upper end of a stem 37 mounted at its lower end in a clamp block 38 which in turn is clamped on the circular portion of the bar 12 near the rectangular end 14. The 105 clamp block has two holes 39, 40, extending therethrough at a right angle to each other through which holes the bar 12 and stem 37

pass. Slots 41, 42, extend respectively from one side of each of said holes outwardly and by means of bolts 43, 44, spanning said slots, the clamp block is gripped on the bar 12 and 5 to the stem 37. Projecting from the perforation in the body 35 on one side thereof is a flaring or conical mouthpiece 45 into which the cigarette rod enters and, passing through the body 35 and into a tubular support 46 extending from the perforation therein on its other side, is cut into lengths by the vibratory movement of the circular knife 21. A steel bushing 47 projects into the slot 36 of the body 35 and has a hole 10 therethrough for the cigarette rod to pass, said bushing coöperating with the circular knife to make clean sharp cuts through the cigarette rod. Because of the novel construction of the clamp block 38, the tubular 15 guide 34 may be adjusted, in every possible direction, vertically, horizontally, and angularly about the axis of the bar 12 and stem 37. The knife 21 may also be adjusted relatively to the tubular guide by loosening the 20 bolts 28, 57 and turning the circular plate 27. 25

Vibratory movement is imparted to the rocking frame 20 and circular knife 21 from a shaft 48 and eccentric 49 thereon the peripheral surface of which is made with a 30 convex curvature in the direction of its axis, and is fitted with a strap 50, the inner face of which has a similar concave curvature to permit the strap rocking laterally on the eccentric. A bar 51 projects from the eccentric 35 strap, in the end of which is formed a socket 52 for a stem 53 adjustable therein and fixed after adjustment by a screw bolt 54. The stem 38 is connected to a block 55 by a horizontal pivot 56, said block in turn 40 being pivoted on the upper circular plate 27 of the frame 20 by a bolt 57.

Constructed as described, with the shafts 18 and 48 geared to move at proper relative speeds, the bar 12 carrying the cutter 21 and 45 tubular guide 34 will be reciprocated longitudinally in the axial line of said bar by the eccentric 17 on shaft 18, at the same time, the frame 20 and cutter 21 will be rocked angularly about the axis of said bar, by eccentric 49, the eccentric strap 50 moving laterally on the eccentric under the longitudinal reciprocation of the frame 20. The movement of the bar 12 in the direction of travel of the cigarette rod will, for a portion 50 of the distance, be at the same speed as the rod, and it is at this time that the knife will advance to cut the rod and then recede to allow said rod to move through the guide on the return movement of the bar 12, a distance sufficient for another cigarette. 55

Attention is called to the fact that the power for reciprocating the bar 12, upon which all the moving parts are carried, is in the exact axial line of said bar, and furthermore, that the rocking frame supporting the 60

knife swings angularly about the same axis. The several parts therefore may be and are made much lighter than usual, and fewer in number; there is a better balance to the moving parts owing to the fact that all lateral or torsional strains are eliminated, which in present devices must be provided for; and by reason of the simple, and light construction and direct movements of the operating parts, the cutting mechanism can be driven 75 at the highest speed without jarring or in any way interfering with the other functions of the cigarette machine.

What I claim is:—

1. In a cut-off mechanism, in combination, 80 a longitudinally movable supporting member, an actuating member having a pivotal connection with said supporting member for imparting reciprocating movement thereto, the axis of said pivotal connection 85 intersecting the central longitudinal axis of said supporting member, a cutter arranged to move longitudinally with said supporting member, and means for rocking said cutter about said central axis while moving with said supporting member.

2. In a cut-off mechanism, in combination, 90 a longitudinally movable supporting member, a cutter supported thereby and arranged to move longitudinally with said supporting member, means for applying a thrust force to said supporting member in opposite directions acting longitudinally of said supporting member at a point in the longitudinal axial line of said supporting 100 member for reciprocating the same, and means for rocking said cutter about said central axis while moving with said supporting member.

3. In a cut-off mechanism, in combination, 105 a slide, a cutter, a supporting arm for said cutter having an axis of rotation on said slide, a guide for said slide, said guide having a geometrical axis coinciding with said first named axis, means for applying a thrust force to said slide in opposite directions acting longitudinally of said slide at a point on the coincident axes to reciprocate said slide, and means for rocking said arm and cutter while said slide is moving. 110

4. In a cut-off mechanism, a longitudinally movable supporting member, means for imparting reciprocating movement thereto having a pivotal connection with said supporting member, the axis of said pivotal connection intersecting the central longitudinal axis of said supporting member, a tubular guide for the article to be cut, a revolving cutter co-acting with said guide, a frame carrying said cutter mounted on said supporting member and movable thereon, and means for rocking said cutter angularly about said central axis while moving longitudinally thereof. 120

5. In a cut-off mechanism for cigarette 130

machines, a pair of spaced guides, a supporting bar mounted to reciprocate longitudinally in said guides, a cigarette rod guide rigidly connected to said bar, a revolving cutter mounted on said bar between said guides to reciprocate with the bar and rock independently thereof, means for reciprocating said bar and the cutter having a pivotal connection with said bar, said 10 pivotal connection having its axis in the central axial line of said bar, and means for rocking said cutter angularly about the said axis.

6. In a cut-off mechanism for cigarette machines, a pair of spaced guides, a supporting bar mounted to reciprocate longitudinally in said guides, a cigarette rod guide rigidly connected to said bar, a revoluble cutter, a swinging frame carrying said cutter mounted on said bar between said guides to reciprocate with the bar and rock independently thereof to carry the cutter to and from said rod guide, means for reciprocating said bar and cutter having a connection with said bar at the end of said bar, and means for rocking said cutter carrying frame on the bar angularly about the same axis.

7. In a cut-off mechanism for cigarette machines, in combination a pair of spaced guides, a supporting bar having angular portions thereon slidable longitudinally in said guides, and an intermediate portion circular in cross section, a frame mounted on said intermediate portion to move longitudinally with said bar and rock trans-

versely thereon, a revoluble cutter carried by and movable with said frame, a cigarette rod guide adjustably mounted on said supporting bar, means for reciprocating said 40 bar, cutter and guide having a connection for actuating the bar attached at the end of said bar, and means for rocking said cutter carrying frame on the bar angularly about said axis to swing said cutter to and from 45 said cigarette guide.

8. In a cut-off mechanism for cigarette machines, a pair of spaced guides, a supporting bar round near its middle portion with ends of other shape slidable longitudinally in said guides, a frame mounted on the middle portion of said bar to move longitudinally therewith and rock transversely thereon, a revoluble cutter carried by and movable with said frame, a cigarette 50 rod guide, a clamp adjustable on the center of said bar and adjustably supporting said guide, means for reciprocating said bar, cutter and guide acting upon said bar at a point in line with the axial center of said bar attached to the bar at the end thereof, and means for rocking said cutter-carrying 55 frame on the bar angularly about said axis to swing the cutter to and from said cigarette guide.

In testimony whereof I have hereunto set my hand in presence of two subscribing witnesses.

JAMES M. HORNADAY.
